UNITED STATES PATENT OFFICE.

HENRY K. MULFORD, OF PHILADELPHIA, PENNSYLVANIA, ASSIGNOR TO NATIONAL DRUG CO., OF PHILADELPHIA, PENNSYLVANIA, A CORPORATION OF PENNSYLVANIA.

HYPODERMIC-SOLUTION CONTAINER.

Application filed August 13, 1926. Serial No. 128,921.

My invention relates to a novel hypodermic solution container and has particular reference to a novel closure therefor, which is so arranged that after the removal of 5 the outer closure with its antiseptic pad, a hypodermic needle or other slender tubular instrument may be inserted through the top of the stopper into the container for the purpose of withdrawing the solution. 10 The antiseptic pad, by contact with the top of the stopper, is adapted to produce a film of antiseptic on said stopper which will serve to sterilize the hypodermic needle passing through the stopper, and also enables the sterilization of the skin or site of 15 injection, by rubbing the top of the stopper over the skin, at the site of injection, prior to the injection.

It is well known to those skilled in the 20 arts of medicine and surgery, that points of hypodermic needles or analogous instruments must be maintained in an absolute antiseptic condition, so as to be used without danger of infecting the patient, and 25 it is also known that solutions such as vaccine, antitoxin, or other medicinal or surgical liquids which are to be injected hypodermically must be kept absolutely uncontaminated by foreign agencies, or otherwise, the solution when injected hypodermically may of itself cause infection.

The principal objects of my invention are, to provide a doubly sealed container 30 for hypodermic or analogous fluids, so arranged that after the removal of an outer closure carrying a disc or pad impregnated with a suitable germicide, the point of a hypodermic needle or analogous instrument may be readily inserted through the top of 40 the stopper into the fluid for the purpose of withdrawing it from the container uncontaminated by exterior agencies, while at the same time sterilizing the instrument which is inserted into the container, since said instrument passes through a film of the 45 germicide on the top of said stopper; to provide a container of the class described provided with a removable disc or pad of antiseptic material which is maintained out of 50 contact with the solution in the container and which therefore does not tend to neutralize or in any way affect the potency of the 55 hypodermic solution; to provide a novel closure for a container of the class described, such that the antiseptic material is main-

tained sealed against the atmosphere by a double seal, as hereinafter explained, thereby preserving the antiseptic character of the closure for an indefinite period; to provide a double sealed closure of the class described, which is capable of being readily pierced by the point of a hypodermic needle or other instrument in order to insert the same into the solution in the container; to provide a double sealed closure of the type last described and having a stopper of such character, as to admit of its being pierced by a hypodermic needle, whereby upon the removal of the needle the mass or body of 60 said stopper will at once assume its normal function as a seal for the container; to provide a doubly sealed closure of the class described, the efficiency of which is not seriously impaired by either a single insertion 65 of the hypodermic needle, or by a plurality of such insertions before the antiseptic character of the seal is destroyed; and finally to provide a novel container closure of the class described of simple design and economical to manufacture, and wherein upon 70 the removal of the outer closure, the top surface of the double seal stopper is at all times impregnated with a film of the germicide or antiseptic carried by the pad in said closure so that said top can be readily applied without further manipulation to 75 the desired part of the human body to render the same aseptic.

My novel device is sanitary and efficient, and entirely dispenses with a swab or applicator contained in a hollow closure in the neck of the container, such as have heretofore been employed.

To the above ends my invention consists of a container and a novel closure, with a double seal therefor in which hypodermic solutions may be retained in bulk, and from which any desired quantity may be withdrawn by the introduction of the needle of a hypodermic syringe, provision being made for excluding atmospheric air from the solution in the container and for preventing the needle of the syringe carrying bacteria or infectious matter into the container during the operations of extracting the contents 100 therefrom.

For the purpose of illustrating my invention I have shown in the accompanying drawings forms thereof which are at present preferred by me, since they will give 110

in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a vertical sectional view of a hypodermic solution container and closure therefor embodying my invention.

Figure 2 represents a perspective view of the double seal closure, prior to the formation of the outer pendant annular flange thereon.

Figure 3 represents on an enlarged scale a perspective view of the outer cap or closure, showing the antiseptic pad or disc therein.

Figure 4 represents on a reduced scale a vertical section of the container seen in figure 1 with the outer closure removed showing also the manner of using the hypodermic needle.

Similar numerals of reference indicate corresponding parts in the figures. Referring to the drawings:—

- 1 designates a suitable bottle or container for hypodermic solutions which is preferably made of glass or similar material having the required aseptic properties and 2 designates my novel closure therefor comprising a hollow stopper 3 which has a readily perforable top membrane of porous rubber and a hollow pendant portion which fits snugly and extends into the major portion of the neck 4 of the bottle. The stopper 3 is initially provided with an exterior shoulder 5, see Fig. 2, and in its initial form has an upper tubular extension 6, which after the insertion of the stopper or plug portion 3 into the mouth of the container is deflected outwardly and downwardly around the upper exterior of the neck of the container so as to form an annular outer pendant flange or skirt 7, which hugs the neck tightly and forms a semi-permanent double seal or closure therefor.
- 50 The stopper 3 and its extension 6 which subsequently forms the pendant, annular, tight fitting flange 7 is preferably made of rubber or similar material, and it will be apparent from the construction seen in Figures 1 and 4 that the contents of the container are effectively sealed and kept uncontaminated from the foreign agencies by a double seal since the hollow stopper 3 extends throughout the major extent of the neck of the container, and in addition the outer annular pendant resilient flange 7 tightly hugs the outer periphery of the neck of the bottle so as to effectively seal the contents thereof.
- 65 8 designates the outer cap or closure which

comprises the cylindrical or shell like body portion 9 having a plurality of upper indentations 10, which frictionally engage the pendant resilient flange 7 at a plurality of points, whereby said closure is retained in position. The upper, outer peripheral portion of said closure is knurled as at 11 and to the inner surface of the top 12 of the closure is permanently or fixedly secured the antiseptic disc or pad 13 which is impregnated with a suitable germicide and is constantly in contact with the top surface 14 of the stopper 3 when the closure 8 is in place, as seen in Figure 1.

The pad 13 may be secured by any suitable adhesive material to the closure 8 and the shoulders 18 of the indentations 10 also secure the pad in position, so that said pad and closure are removable as a unit, as will be understood from Fig. 3, whereby upon their removal the top surface 14 of the stopper having a film of the germicide or sterilizing material thereon is immediately accessible for application to the desired part of the human body to render the same aseptic.

15 designates the needle of a hypodermic syringe 16.

In practice after the hypodermic solution has been initially introduced into the previously sterilized receptacle 1, the plug portion of the stopper 3 is forced tightly into the mouth of the container, so as preferably to occupy the major portion of the neck thereof. The tubular extension 6, seen in Fig. 2, is then deflected downwardly to form the outer pendant, annular sealing flange 7 which tightly hugs the neck of the container so that the latter is sealed exteriorly and interiorly throughout practically the entire length of its mouth and neck, the mouth of the container being sealed at its top and down its sides by the annular pendant flange 7.

By reason of the double seal afforded by the inner wall of the stopper 3 and the outer, annular, pendant flange 7, the mouth of the container is obviously effectively and doubly sealed in a semi-permanent manner against contaminating agencies. As the outer closure or cover 8 has the pad or disc 13 permanently or fixedly secured thereto by means of the indentations of the cap holding the antiseptic firmly in position in the top of the cover, as will be understood from Figs. 1 and 3, it will be apparent that when said closure is placed in position, as seen in Fig. 1, the indented portions 10 will be positioned opposite the top bead 17 of the bottle, as seen in Fig. 1, and will spring inwardly and tightly and fixedly engage the contiguous portions of the flange 7 which are immediately below said upper bead.

By this construction, the antiseptic pad 13 is held with the requisite tightness against

the top 14 of the stopper 3, so that there will at all times be a film of the germicide upon the top 14. In order to withdraw the charge of the solution by means of a hypodermic 5 syringe or needle, the closure 8 with its pad 13 is removed from the container. The nose or point 15 of the needle is thrust forcibly through the elongated body portion of the stopper 3 until it enters the solution a sufficient distance to permit the withdrawal of the proper amount of the fluid therein.

Prior to the needle 15 assuming the position seen in Fig. 4, it will be understood that 15 the effect of pushing the point or nose of the needle through the antiseptic film on the surface 14 will be completely to sterilize the point of the needle and such part of its length as comes in contact with the film 20 of the disinfectant carried within the outer surface at the top 14 of the stopper 3, which is a readily perforable body of rubber.

After the mechanism of the needle has been properly manipulated to draw up the 25 required charge of fluid in the container 1, the nose of the syringe is withdrawn, and the closure 8 replaced in the position seen in Fig. 1.

It will be obvious that, owing to the semi-permanent engagement of the plug 3 and the 30 pendant flange 7 with the upper portion or mouth of the container, the solution therein contained is uncontaminated by outside agencies and will retain its original properties 35 for an indefinite period of time.

The container 1 may be of sufficient capacity to receive a number of hypodermic doses or injections and a succession of antiseptic charges of fluid may be successively removed from the container in the above 40 described manner without destroying the hermetically sealed character of the receptacle closure.

This end is attained by making the top of 45 the stopper 3 of soft rubber of the requisite thickness so that when the point of the needle is withdrawn, there will be a sufficient thickness, which will immediately close up and restore the seal to its original efficiency, 50 thus enabling the maintenance of sufficient contracting force to afford a perfectly self sealed container, notwithstanding said needle may be many times introduced through the top 14 of the stopper 3 before all the 55 contents of the container is removed, as contradistinguished to prior devices of this general character, wherein there is only a relatively thin membrane or wall of rubber to be pierced by the nose or point of the needle.

My present invention differs from prior 60 devices having a removable pendant swab since I dispense with such swab entirely, and use a stopper having inner and outer, 65 annular, pendant, resilient flanges, which tightly hug the top of the bottle and the

exterior periphery of the mouth thereof. The top 14 of the rubber closure 8 being impregnated with the antiseptic solution carried in the pad 13 preferably of felt or other absorbent substance, is used to sterilize 70 the skin or site of injection insuring an antiseptic or sterile injection.

It will now be apparent that I have devised a new and useful hypodermic solution container, which embodies the features of 75 advantage enumerated as desirable in the statement of the invention and the above description, and while I have, in the present instance shown and described forms thereof which will give in practice satisfactory and reliable results, it is to be understood that such preferred embodiments are susceptible of modification in various particulars, without departing from the spirit or scope of the invention or sacrificing any 80 of its advantages.

Having thus described my invention, what I claim as new and desire to secure by Letters Patent is:—

1. In a container for hypodermic solutions having an outwardly facing sealing mouth, a stopper of readily perforable impervious material closed at its top and having a pendant annular inner wall tightly fitting said mouth and provided with an outer integral, pendant, annular resilient flange snugly engaging the top and outer periphery of said mouth, an outer closure for said stopper comprising a top, and an integral annular wall frictionally and tightly engaging the outer flange of said stopper, and a pad impregnated with an antiseptic fixedly secured to the inner surface of the top of said closure and adapted normally to contact with the top surface of said stopper to form thereon an antiseptic film, thereby preventing a needle from carrying bacteria into said container, and enabling sufficient antiseptic to be used in rendering sterile the skin or site of injection, 95 said closure and pad being removable as 100 a unit.

2. In a container for hypodermic solutions having an outwardly facing sealing mouth provided with a top bead, an elongated stopper of readily perforable impervious material closed at its top and having a pendant annular inner wall fitting tightly in the major portion of the container neck and provided with an outer integral, pendant, annular, resilient flange snugly engaging the top and outer periphery of said neck, an outer closure for said stopper comprising a top and an integral annular wall frictionally and tightly engaging the flange of 115 said stopper, a pad impregnated with an antiseptic positioned against the inner surface of said top and adapted normally to contact with the top of said stopper to form 120 thereon a sterilizing film, thereby prevent- 125

- ing the needle from carrying bacteria into said container, said closure and pad being removable as a unit, and inwardly deflected indentations in said closure adapted to compress portions of said outer pendant flange against the container neck. 30
3. In a container for hypodermic solutions having an outwardly facing sealing mouth provided with a top bead, an elongated stopper of readily perforable impervious material closed at its top and having a pendant annular inner wall fitting tightly in the major portion of the container neck and provided with an outer integral, pendant, annular, resilient flange snugly engaging the top and outer periphery of said neck, an outer closure for said stopper comprising a top and an integral annular wall frictionally and tightly engaging the flange of said stopper, a pad impregnated with an antiseptic positioned against the inner surface of said top and adapted normally to contact with the top of said stopper to form thereon a sterilizing film, thereby preventing the needle from carrying bacteria into said container, said closure and pad being removable as a unit, and inwardly deflected indentations in said closure adapted to compress portions of said outer pendant flange against the container neck and said indentations having upper shoulders engaging said pad to retain the latter in position within said closure. 35
4. In a container for hypodermic solutions, having an outwardly facing sealing mouth, a stopper having a readily perforable impervious top tightly fitting said mouth and provided with an outer integral, pendant, annular resilient flange, snugly engaging the top and outer periphery of said mouth, an outer closure for said stopper comprising a top, and an annular pendant wall, frictionally and tightly engaging the outer flange of said stopper, and a pad impregnated with an antiseptic, fixedly secured to the inner surface of the top of said closure and adapted normally to contact with the top surface of said stopper to form thereon an antiseptic film adapted to effect a sterilization of a hypodermic needle while passing through said top of said stopper and also for enabling the sterilization of the skin or site of injection by the application of the film of antiseptic carried by the top of the stopper, by direct contact of said stopper with the skin, said closure and pad being removable as a unit. 40 45 50 55

HENRY K. MULFORD.
